UNITED STATES PATENT OFFICE.

THOMAS L. RANDALL, OF CENTERVILLE, MISSOURI, ASSIGNOR OF ONE-HALF TO T. J. DOBIN, OF CENTERVILLE, MISSOURI.

HORSESHOE.

942,012.

Specification of Letters Patent. Patented Nov. 30, 1909.

Application filed June 4, 1909. Serial No. 500,105.

To all whom it may concern:

Be it known that I, THOMAS L. RANDALL, a citizen of the United States, residing at Centerville, in the county of Reynolds, State 5 of Missouri, have invented certain new and useful Improvements in Horeshoes; and I do hereby declare the following to be a full, clear, and exact description of the invention, such as will enable others skilled in the art to 10 which it appertains to make and use the same.

This invention relates to horse shoes, more particularly to "cushion" horse shoes, and has for one of its objects to simplify 15 and improve the construction and increase the efficiency and utility of devices of this character.

The improved device comprises in general a body portion in horse shoe form and 20 adapted to be connected to the hoof by nails in the usual manner and reduced in thickness at the heel and toe portions, two bearing plates reduced in thickness at their end portions and conforming in outline when 25 combined with the upper or body portion and meeting beneath the toe portions of the body, the bearing plates having the heel and toe calks depending therefrom, and means for connecting the plates detachably to the 30 body.

The invention consists in certain novel features of construction as hereinafter shown and described and then specifically pointed out in the claims, and in the drawings 35 illustrative of the preferred embodiment of the invention, Figure 1 is a top plan view of the improved device. Fig. 2 is a bottom plan view of the same. Fig. 3 is a side elevation. Fig. 4 is a front elevation. Fig. 5 is a side elevation illustrating a modification in the construction. Fig. 6 is a transverse section on the line 6—6 of Fig. 5.

The body portion of the shoe is indicated at 10 and conforms in shape with an ordinary 45 horse shoe, and is provided with the usual nail apertures 11 to enable the body to be attached to the hoof in the ordinary manner. At the heel and toe portions the body 10 is reduced in thickness as illustrated 50 in Fig. 3, and is provided with apertures to receive holding screws, as hereinafter explained.

Bearing beneath the body 10 are two bearing plates 12—13 conforming in outline to

the body 10 and meeting beneath the toe 55 portion of the body.

The bearing plate 12 is provided with a heel calk 14 while the plate 13 is provided with a heel calk 15. The plate 12 is also provided with a half calk 16 while the 60 plate 13 is provided with corresponding half calk 17, the two calks 16—17 being located beneath the toe portion of the body and constituting the toe calk of the shoe. The plates 12—13 are reduced in thickness toward their 65 ends similar to the body 10 so that relatively large spaces are formed between the toe and heel portions of the body and the plates, as shown. The plates 12—13 are provided with apertures to receive the holding screws 18 70 whereby the plates are connected detachably to the body, the screws operating in the threaded apertures in the body above referred to.

By this simple means a very effectual and 75 efficient cushion shoe is produced which relieves the horse largely from jars and concussions incident to travel over pavements or stony or hard roads. The body 10 and the plates 12—13 should be of sufficient strength 80 so that they will not yield under ordinary conditions, or when the horse is standing or traveling over relatively soft roads, but when the horse is moving over stone or other hard pavements, or upon stony hard roads, 85 the reduced portions of the shoe will produce a cushioning effect, and relieve the horse from strains as above noted.

In Figs. 5 and 6 rubber or other filling members are arranged between the reduced 90 portions of the body and the plates, to not only receive the downward movement when strains are applied, but likewise to prevent the entrance of stones or other matter which might enter the cavities and prevent the 95 desired action of the shoe. The filler members are indicated by the character 19, and are preferably formed with hollows in their upper faces to form ribs to bear upon opposite sides of the body 10, and thus prevent 100 the displacement of the filler members. The filler members may be formed of any suitable material, such as relatively hard rubber, or the like, and extend entirely around the shoe, but are relatively thin where the parts 105 are united by the fastening devices 18.

The improved device can be readily applied to shoes of various forms and sizes,

and adapted to all the various qualities of shoes manufactured and to hoofs of varying sizes, without material structural changes.

What is claimed is:—

- 5 1. A horse shoe comprising a body member reduced in thickness at the heel and toe portions, two bearing members reduced in thickness at the ends and each corresponding in outline to one-half of the body, said bearing members each having a heel calk and a half toe calk, and means for detachably securing said bearing members to the body.
- 10 2. A horse shoe comprising a body member reduced in thickness at the heel and toe portions, two bearing members reduced in thickness at the ends and each corresponding in outline to one-half the body and meeting beneath the toe portion of the same, said bearing members each having a heel calk at its rear end and half calks at its forward

meeting end and combined to constitute the toe calk of the shoe, and means for detachably securing said bearing members to the body.

25 3. A horse shoe comprising a body member reduced in thickness at the heel and toe portions, two bearing members reduced in thickness at the ends, and each corresponding in outline to one-half of the body and each of said bearing members having a heel calk and a half toe calk, means for detachably securing said bearing members to the body, and yieldable filler members between the reduced portions of the body member 30 and the bearing members.

35 In testimony whereof, I affix my signature, in presence of two witnesses.

THOMAS L. RANDALL.
